UNITED STATES PATENT OFFICE.

CLARKSON A. DISBROW, OF NEW ROCHELLE, NEW YORK, ASSIGNOR TO THE RAIL JOINT COMPANY, OF NEW YORK, N. Y., A CORPORATION OF NEW YORK.

COMPOSITE WEAR PLATE FOR RAIL JOINTS.

Application filed February 16, 1927. Serial No. 168,704.

This invention relates to rail joints, and more particularly to a rail joint construction including a novel wear unit having the capacity for taking the wear; adapting the unit to joint bars and rails of different vertical height and fishing space; and also rendering the joint bars more adaptable to the wave motion of the rails.

To that end the invention contemplates the provision of a unit comprising a wear plate to be placed between the joint bar and the rails and filler abrasion plates adapted to provide more or less additional thickness to fit the fishing space of the rail. In that connection it may be observed that one of the advantages of the invention is to provide a construction which minimizes the effect of any irregularity in the roll surfaces of both the rails and the joint bars, while at the same time permitting the bars to be used on rails of different fishing spaces.

A further object of the invention is to provide a composite wear plate for rail joints which is separate from the joint bar, that is, separately handled or applied, but cooperating therewith when the joint bars are assembled to constitute the joint.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings in which

Figure 1 is a perspective view of a joint embodying the present improvements.

Figure 2 is a vertical half-sectional view illustrating a modification of the construction shown in Fig. 1.

Figures 3, 4, 5 and 6 are additional vertical half-sectional views illustrating the range of modification of the invention.

Similar reference characters designate corresponding parts throughout the several figures of the drawings.

In its primary aspect the present invention contemplates the combination of a rail joint bar designated generally as A and the composite wear plate or unit B which is adapted to be inserted in the fishing space of the rails R—R. The said unit B comprises a wear plate 1 having an upper out-

wardly extending bearing flange 2 and a lower outwardly extending flange 3 connected by an intermediate web portion w^1 which is preferably bowed for flexibility; and the said flanges 2 and 3 cooperate with 60 filler abrasion plates 4 and 5 respectively located at the head and foot of the bar to complete the unit.

Therefore, the essential features and characteristics of the invention involve the use 65 of a wear plate including offset flanges adapted to cooperate with filler abrasion plates which may be interlocked with the flanges in any suitable and practical manner, as for example by welding.

The filler abrasion plates 4 and 5 may be of any desired or required length, but are preferably relatively short strips of metal arranged at spaced intervals along the flanges of the wear plate to provide full 75 fishing height for the bar A at intervals and thus form well located bearing surfaces between the completed bar and the rail bearing surfaces.

The above described fundamental features 80 may be embodied in various structural forms as will be apparent from the drawings. For example Figure 1 of the drawings illustrates the abrasion plates 4 and 5 arranged between the head and foot of the bar A and 85 the flanges 2 and 3 of the wear plate, while the web of the wear plate is slightly bowed outwardly to provide vertical adjustment and resiliency to the plate thereby enabling it to accommodate and adjust itself to conditions existing between the bar and fishing surfaces of the rail.

Figure 2 illustrates the same relative arrangement of filler abrasion plates with reference to the flanges of the wear plate, and 95 the bowed web of the latter follows the contour of the rail web.

Figures 3, 4 and 6 of the drawings illustrate the use of the filler abrasion plates between the flanges 2 and 3 of the wear plate 100 in the fishing surfaces at the head and foot of the rail. In Fig. 3 the web w^2 follows the contour of the web of the joint bar while in Figure 4 the web w^4 is bowed outwardly but out of contact with the web of the joint 105 bar, while Figure 6 illustrates the web w^6 of the wear plate following the inside face of the bar and the upper and lower flanges thereof being offset as indicated at 2^a and 3^a to engage with an outer face of the bar. 110

In Figure 5 the flanges 2 and 3 of the wear plate are arranged between the upper filler abrasion plates 4 and 4^a and lower abrasion plates 5 and 5^a, respectively, while the web portion *w*⁵ is longitudinally corrugated or crimped. In this construction the wear plate is formed so as to provide for a considerable variation in the fishing height of the rails, and hence by varying the thickness 10 of the plates combined with it, it may be used as is the joint bar, for rails of different fishing:

From the foregoing it will be apparent that the present invention involves the use 15 of a main or primary joint bar A which may be of standard cross sectional shape or design but preferably of smaller section and less vertical height than the fishing space of the rail with which it is intended to be used, 20 but which constitutes in effect a base or carrier for the present wear unit which consists of the hard metal wear plate and acts as an abrasion plate to take up wear between the joint bar and the rails, together with 25 spaced strips or plates acting as fillers to provide the additional thickness required to fill the fishing spaces of the rails. By reason of the fact that the bar A is usually and preferably of less fishing height than that of 30 the rails, the same may be readily made available for use in connection with rails of different section thereby effecting economy in the cost of rails and the handling of the same. Furthermore, in use, the combined 35 wear plate and joint bar provide a rail joint construction of increased life and efficiency while at the same time, contributing to the vertical flexibility of the joint, as well as facilitating the initial application or in- 40 stallation.

Without further description it is thought that the features and advantages of the invention will be readily apparent to those skilled in the art and it will of course be 45 understood that changes in the form, proportion and minor details of construction may be resorted to, without departing from the spirit of the invention and scope of the appended claims.

50 I claim:—

1. A rail joint including in combination with the rails, a joint bar of uniform section throughout, a flanged metal wear plate, and separate filler abrasion plates cooperative with the flanges of said wear plate.

2. A flexible rail joint including in combination with the rails, a joint bar, a flanged metal wear member, and filler abrasion plates engaging the flange of the wear plate.

60 3. A rail joint including in combination

with the rails, a joint bar of uniform section throughout and of less fishing height than the fishing surfaces of the rail, a hard metal flanged wear plate arranged between the joint bar and the rail, and abrasion plates cooperative with the flanged wear plate and arranged in spaced relation to maintain proper fishing for the joint bar at intervals throughout the joint. 65

4. A rail joint including in combination with the rails, a joint bar of less fishing height than the fishing surfaces of the rails and of uniform section throughout, and separate abrasion plates arranged in spaced relation and respectively against the top and bottom flanges of the wear plate and combining therewith to maintain the proper fishing for the joint bar. 75

5. A rail joint including in combination with the rails, a joint bar of less fishing height than the fishing surfaces of the rails and of uniform section throughout, and separate abrasion plates arranged in spaced relation at one side of the flanges of the wear plate and cooperating therewith to maintain the proper fishing for the joint bar. 80

6. A flexible rail joint including in combination with the rails, a uniform-section joint bar of less fishing height than the fishing surfaces of the rail, a hard metal flanged wear plate lying within the fishing spaces of the rails and whose flanges overlie respectively the head and foot of the joint bar and separate abrasion plates arranged in longitudinal spaced relation and respectively against the top and bottom flanges of the wear plate and combining therewith to maintain the proper fishing for the joint bar. 90

7. In a rail joint, the combination with the rails and a joint bar of less fishing height than the fishing spaces of the rails, a wear unit comprising a wear plate of channel formation having flanges interposed between the head and foot of the bar and the head and foot of the rail respectively, and longitudinally spaced abrasion plates cooperating with the said flanges. 100

8. A flexible rail joint including rails, a joint bar of uniform section throughout, a flanged metal wear plate fitting the fishing surfaces of the rails, and separate filler abrasion plates interposed respectively between the head and foot of the joint bar and the flanges of the wear plate. 110

In testimony whereof I hereunto affix my signature.

CLARKSON A. DISBROW.
